UNITED STATES PATENT OFFICE

170,660

FRUIT BOWL

Lyall Mellor Ross, Balwyn, Victoria, Australia

Application February 12, 1953, Serial No. 23,592
In Australia December 4, 1952

Term of patent 14 years

(Cl. D36—2)

To all whom it may concern:

Be it known that I, Lyall Mellor Ross, a British subject, residing at Balwyn, in the State of Victoria, Commonwealth of Australia, have invented a new, original, and ornamental Design for a Fruit Bowl, of which the following is a specification, reference being had to the accompanying drawing, forming part thereof.

I claim:

The ornamental design for a fruit bowl, as shown.

LYALL MELLOR ROSS.
